UNITED STATES PATENT OFFICE.

CHARLES A. TAYLOR, OF CHICAGO, ILLINOIS.

DESIGN FOR TRUNK-FIXTURES.

Specification forming part of Design No. **11,524**, dated November 25, 1879; application filed October 25, 1879.
[Term of patent 7 years.]

To all whom it may concern:

Be it known that I, CHARLES A. TAYLOR, a citizen of the United States of America, residing at Chicago, in the county of Cook and State of Illinois, have invented and produced a new and original Design for Trunk-Fixtures, of which the following, in connection with the accompanying drawings, is a specification.

Figure 1 is a perspective view of a trunk provided with fixtures embodying my invention; Fig. 2, a front view of one of the fixtures detached, and Fig. 3 a perspective of the same.

My design relates to metallic fixtures employed on the outside of trunks, and to that particular class of such fixtures as are made angular for application to the corners of the trunk, so as to lap two or more faces thereof.

A A represent fixtures of the particular or specific class above referred to. a is the central portion of the fixture, which may be described as a comparatively long and narrow panel bent at a right angle along its longitudinal center. a' a' are wings or leaves extending laterally from the part a. Each wing a' a' consists, essentially, so far as relates to mere design or configuration, of two crescent-

shaped parts, e e, arranged with their convex edges toward each other, or having that appearance, as shown, and, by preference, so as to make the outer ends of the wings somewhat narrower than the inner end.

The outer ends of the wings are perforated, and between the diverging parts of the crescents may be arranged fillets or dart-heads, as shown.

The face of the crescents may be either plain or paneled; but the essential feature of my design, so far as relates to the wings, is the double crescent-shaped appearance now fully described.

I claim—

The design for corner-plates for trunks, substantially as herein shown and described, the same consisting, essentially, of the oblong-appearing center a and of the wings a' a', the latter having the appearance and consisting of crescent-shaped parts arranged back to back.

CHARLES A. TAYLOR.
